UNITED STATES PATENT OFFICE.

WILLIAM F. BOCKHOFF, OF RICHMOND, INDIANA, ASSIGNOR TO THE NATIONAL AUTOMATIC TOOL COMPANY, OF RICHMOND, INDIANA, A CORPORATION OF INDIANA.

SUCCESSIVE PULLEY DRIVE FOR DRILLING MACHINES.

Application filed February 26, 1924. Serial No 695,250.

This invention relates to power transmitting mechanisms and is applicable particularly to machine tools such as drilling machines provided with a plurality of independent trains of mechanism each of which receives power from a common actuator.

Drilling machines, as commonly constructed, are provided with a drill-spindle rotating mechanism and a spindle feeding mechanism, of which the former is suitably connected with the actuator to rotate the drills, while the latter is adapted to effect a relative feeding movement between the drill and the work-supporting table, to cause the drill to be fed into the work.

It is to be understood that, as normally actuated, the ratio between the spindle rotating mechanism and the feeding mechanism is such that maximum efficiency is obtained under normal working conditions.

Heretofore, power has been transmitted to these two mechanisms by separate connections with a motor, power shaft or other common actuator. Usually the drill-spindle rotating mechanism was connected with the actuator by a suitable belt while the feeding mechanism was positively driven therefrom by gear mechanism. With this construction the feed of the drill was positive while its rotation was impositive.

Considerable difficulty has heretofore been experienced in the operation of drilling machines so constructed due to slippage of the spindle-rotating belt when the machine was operating under a heavy load. This slippage caused a reduction in the speed of rotation of the spindles and the drills carried thereby while the feed, being geared direct to the actuator, continued at its predetermined speed, with the result that the drill was fed into the work faster than it could remove the metal, whereby a severe strain was thrown upon the feeding mechanism and the machine column and the drills were occasionally broken and the work impaired.

This invention has for an object to provide a power transmitting device wherein a plurality of interconnected trains of mechanism are actuated from a common actuator and in which the failure of one of the trains will effect the action of another train.

More specifically, this invention has for an object to provide a drilling machine with a power transmitting mechanism including a common actuator and spindle feeding and

rotating devices actuated thereby, so constructed and arranged that any slippage in the spindle rotating device will cause a slowing down in the speed of the feed.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Fig. 1 is a side elevation of a drilling machine embodying the present invention and Fig. 2 is an enlarged detail sectional view showing more clearly the connection between the common actuator and the spindle rotating and feeding mechanisms.

Referring more particularly to the drawings the invention is shown embodied in a conventional form of drilling machine comprising a base 1 supporting a standard 2 upon which is mounted for vertical bodily movement, a drill-spindle head 3, within which is adjustably secured drill-spindles as 4 (of which only one is shown) fitted with drills as d.

A work-table 5 is also mounted for vertical adjustment on the standard 2 beneath the head 3 and is adapted to hold the work to be operated on by the drills d.

As before stated, the drill spindles are rotated and the head 3 is moved vertically on the standard by a common actuator, and this invention deals with the means for transmitting power from the actuator to the mechanisms for effecting the rotation of the spindles and the feed of the drills into the work.

In accordance with this invention, the spindles are rotated and the drills are fed into the work by power supplied by a common actuator, preferably an electric motor A which, through suitable connections later to be described, rotates a primary pulley 6. Within the upper end of the standard 2 is journaled a horizontal shaft 7, connected by gears (not shown) to a vertical shaft 8 which, through suitable means common to machines of this type, rotates the drill spindles and the drills carried thereby. Upon one end of the

shaft 7 there is secured a pulley 9 connected by means of a belt 10, with the primary pulley 6.

The head 3 is moved vertically on the standard, to cause the drills *d* to enter and emerge from the work, by a suitable power feed indicated generally as *f*.

Inasmuch as the feeding mechanism and the spindle rotating mechanism are common to machines of this type and are well understood, detailed illustration and description thereof is deemed unnecessary.

The means for rotating the pulley 7 from the actuator A preferably comprises a pinion 11 secured to the motor-shaft, which pinion meshes with a gear 12 non-translatably journaled on a shaft 13 fixed in bearings 14 carried by the machine base. The gear 12 is provided with a hub 15 to which the pulley 7 is secured by set screws, as 16.

Loosely journaled upon the shaft 13, coaxial with the pulley 6, and of like diameter, is a relatively narrow feed actuating pulley 17 supporting a pinion 18 which forms a part 25 of the feeding mechanism *f*.

It will be observed that the combined widths of the pulleys 6 and 17 are substantially the same as the pulley 9 and therefore, due to the increased width of the pulley 9, the friction 30 between the belt 10 and pulley 9 is greater than between the belt and the pulley 6 and therefore any slippage between the motor and the spindle-rotating mechanism will take place around the pulley 6.

Further as the pulley 17 is connected with the actuator only through the belt 10 any slippage of the belt on the pulley 6 which would slow down the rotation of the spindles 35 will likewise effect a reduction in the speed of the feeding mechanism.

The belt 10 virtually comprises two independent belts jointed together along the vertical plane between the pulleys 6 and 17 and is, in effect, two distinct belts one connecting 45 the pulley 6 with the pulley 7 and the other connecting the pulley 7 with the pulley 17; and it is to be understood that this invention contemplates the use of such a double belt connection.

This arrangement prevents overloading the machine through excessive feeds caused by a slowing down of the spindle driving mechanism.

From the foregoing description, it will be 55 apparent that there has been provided a power transmitting mechanism for effecting the rotation and feed of drill-spindles from a common actuator, and in which the feeding mechanism is affected by any failure of the spindle rotating mechanism.

Without further analysis, the foregoing will so fully reveal the gist of this invention that others can, by applying current knowledge, readily adapt it for various utilizations 60 by retaining one or more of the features that,

from the standpoint of the prior art, fairly constitute essential characteristics of either the generic or specific aspects of this invention, and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. Apparatus of the class described, comprising a work-support, a tool-carrier, means to cause relative feeding movement of said work-support and tool-carrier, means to impart to said tool-carrier an operative movement in predetermined ratio with said relative feeding movement, and means to compensate for casual adventitious variations in said ratio, said means including co-axial driving and driven pulleys of unequal widths, a belt driven by one of said pulleys and driving the other of said pulleys; and independent trains of mechanism driven respectively by the belt and said last named pulley.

2. A power-transmitting mechanism comprising driving and driven pulleys of substantially equal diameter and arranged coaxially in proximity, and a belt arranged to run in constantly predetermined unequal bridged relation upon the joint periphery of said pulleys, said pulleys being capable of relative rotation, whereby, if one of said pulleys be retarded, another of said pulleys may 100 rotate with said belt, the latter slipping upon said retarded pulley.

3. A multiple-spindle drill, comprising a work-support, a plurality of drill-spindles, means to rotate said spindles, means to feed said spindles toward said work-support, and means to compensate for casual variation in the predetermined ratio between the operative speed of said spindles and said feeding movement, said means including a plurality of 105 coaxially arranged pulleys; an operative connection between one of said pulleys and said spindle rotating means; and an operative connection between another of said pulleys and said spindle feed, said first named operative 110 connection including a belt bridging the joint peripheries of said pulleys and having a constant unequal contact with said pulleys.

4. A power-transmitting mechanism combining a driving pulley, a belt driven thereby, said belt overhanging one edge of said pulley, a second pulley, remote from said driving pulley, driven by said belt, a third pulley, adjacent said first named pulley and co-axial therewith, driven by the overhanging portion of the belt; and independent trains of mechanism driven by said second and third pulleys.

5. A power-transmitting mechanism for drilling-machines comprising a primary 130

driving pulley, a feed driving pulley adjacent and co-axial with said first named pulley and of substantially equal diameter; a belt circumscribing said pulleys, the width of said belt being substantially the combined width of both of said pulleys; a pulley driven by said belt, the width of said third pulley being equal to the width of the belt, and independent trains of mechanism driven by said second and third pulleys.

6. A friction drive comprising a driving element; a driven element; a frictional driving connection between said elements, said driving and driven elements being so constructed and arranged that the friction between the driven element and the driving connection is greater than the friction between the driving element and the driving connection, a second driven element co-axial with said driving element also driven by said driving connection, and independent trains of mechanism driven by said driven elements.

7. A power transmitting mechanism combining first and second driven elements; a driver co-axial with said second driven element; a single friction drive for transmitting motion from said driver to said first driven element, said friction drive also being adapted to transmit motion from said driver di-

rectly to said second driven element independently of said first driven element; a spindle rotating mechanism actuated by said first driven element; and a spindle feeding mechanism actuated by said second driven element.

8. A friction drive comprising a prime-mover; two independent trains of mechanism actuated thereby, said trains being connected to a single element to give to said element two distinct movements; frictional connections between said prime-mover and said mechanisms including a driving member common to both mechanisms, and friction means independently connecting said member with first and second driven elements each specific to one of said trains, the friction between said driving member and said connecting means being greater than the friction between the connecting means and the first driven member and less than the friction between the said connecting means and the second driven member, one of said driven members being mounted co-axial with said driving member.

In witness whereof, I hereunto subscribe my name.

WILLIAM F. BOCKHOFF.
